CLAIM

We claim the ornamental design for a television receiver, as shown and described.

DESCRIPTION

FIG. 1 is a front perspective view of a television receiver showing our new design;

FIG. 2 is a rear perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a front perspective view showing the claimed design in a state of use with an environmental stand;

FIG. 10 is a front perspective view of the television receiver showing the environmental screen in a flat state of use;

FIG. 11 is a rear perspective view thereof;

FIG. 12 is a front elevation view thereof;

FIG. 13 is a rear elevation view thereof;

FIG. 14 is a left-side elevation view thereof;

FIG. 15 is a right-side elevation view thereof;

FIG. 16 is a top plan view thereof;

FIG. 17 is a bottom plan view thereof; and,

FIG. 18 is a front perspective view showing the claimed design in a state of use with an environmental stand.

The broken lines shown in the drawings represent portions of the television receiver that form no part of the claimed design. The broken lines showing of the stand in FIGS. 9 and 18 is for the purpose of illustrating environment and form no part of the claimed design.

1 Claim, 18 Drawing Sheets
